UNITED STATES PATENT OFFICE

115,987

DESIGN FOR AN ORNAMENTAL BELT

Charles Wahl, New York, N. Y.

Application June 1, 1939, Serial No. 85,282

Term of patent 3½ years

To all whom it may concern:

Be it known that I, Charles Wahl, a subject of the Kingdom of Hungary and resident of New York city, in the county and State of New York, have invented a new, original, and ornamental Design for an Ornamental Belt, of which the following is a specification, reference being had to the accompanying drawing, forming a part thereof, and of which Figure 1 is a perspective view in closed position of an ornamental belt showing my new design, and Fig. 2 is a fragmentary view in elevation thereof in open flat position, and Fig. 3 is a fragmentary view in front elevation of the belt closing end links thereof in inter-engaged position.

I claim:

The ornamental design for an ornamental belt, substantially as shown.

CHARLES WAHL.
